DESIGN FOR A DISPLAY CASE

Franklin J. Petzke, Minneapolis, Minn., assignor to Johnson Nut Company, Minneapolis, Minn.

Application October 22, 1937, Serial No. 72,373

Term of patent 3½ years

To all whom it may concern:

Be it known that I, Franklin J. Petzke, a citizen of the United States, residing at Minneapolis, in the county of Hennepin and State of Minnesota, have invented a new, original, and ornamental Design for a Display Case, of which the following is a specification, reference being had to the accompanying drawings, forming a part thereof,

Figures I and II are a front perspective view and a rear perspective view respectively of the display case showing my new design.

I claim:

The ornamental design for a display case as shown.
